United States Patent Office

Des. 221,778
Patented Sept. 7, 1971

221,778

DRESSER OR SIMILAR ARTICLE

Thomas Szirmay, Montreal, Quebec, Canada, assignor to Wentworth Industries Limited, Montreal, Quebec,
Canada

Filed Apr. 14, 1969, Ser. No. 16,708

Claims priority, application Canada Oct. 15, 1968

Term of patent 14 years

Int. Cl. D6—04

U.S. Cl. D33—6

FIG. 1 is a front elevational view of a dresser showing the new design;

FIG. 2 is an end elevation of FIG. 1;

FIG. 3 is a top plan view;

FIG. 4 is a fragmentary vertical section on line 4-4 of FIG. 1; and

FIG. 5 is a section on line 5-5 of FIG. 1.

The side opposite FIG. 2, and not shown, is a mirror image of FIG. 2, while the back of the article is essentially flat.

I claim:

The ornamental design for a dresser or similar article, as shown and described.
